CATAMARAN SAILBOAT

Hobart L. Alter, Capistrano Beach, Calif., assignor to Coast Catamaran Corporation, Capistrano Beach, Calif.

Filed Aug. 5, 1970, Ser. No. 24,326

Term of patent 14 years

Int. Cl. D12—06

U.S. Cl. D71—1

FIG.1

FIG.6

FIG. 1 is a front perspective view of a catamaran sailboat showing my new design;

FIG. 2 is a side elevational view of said boat in enlarged scale and with the upper portion of the mast and sails being deleted in the interest of clarity;

FIG. 3 is a top plan view of said boat;

FIG. 4 is an elevational view of the side opposite that shown in FIG. 2, with the mast and sails being deleted in the interest of clarity;

FIG. 5 is a front elevational view of said boat; and

FIG. 6 is a fragmentary rear elevational view of said boat.

I claim:

The ornamental design for a catamaran sailboat, substantially as shown and described.
